UNITED STATES PATENT OFFICE.

A. AUGUSTUS LOW, OF BROOKLYN, NEW YORK, ASSIGNOR TO THE ALDEN
TYPE MACHINE COMPANY, OF NEW YORK, N. Y.

TYPE-CONTAINING CHANNEL.

SPECIFICATION forming part of Letters Patent No. 360,104, dated March 29, 1887.

Application filed March 19, 1886. Serial No. 195,866. (No model.)

To all whom it may concern:

Be it known that I, A. AUGUSTUS Low, a citizen of the United States, residing in the city of Brooklyn, in the county of Kings and State of New York, have invented certain new and useful Improvements in Type-Containing Channels, of which the following is a specification.

My present invention relates to the special construction of the type-channels in which the types are arranged in a prescribed position for use in conjunction with the class of type setting and distributing apparatus set forth in Patents Nos. 230,784, 254,019, 263,707, 264,084, 264,085, 268,409, 271,711, 275,664, 279,168, and 282,988.

In the method of handling types to which my invention appertains the types are deposited successively into the ends of their respective containing-channels, while the latter rest with their backs or spines upon the table or bed of the distributing apparatus, each line of type being forwarded within its channel as succeeding types are received. The forwarding of the types is usually accomplished by a reciprocating pusher at the receiving end of the channel acting against the resistance of the column of type and that afforded by a "slug" or movable support which precedes and sustains the types in the required upright position.

In my application No. 192,493 I describe and claim a means for counteracting the retractile tendency or "backlash" of the types in the containing-channel, consisting of a semi-elastic section or surface arranged upon one of the side walls of the type-channel.

It will be unnecessary to describe herein more definitely the nature and causes of backlash, since by reference to the said application No. 192,493, and to No. 156,604, filed February 14, 1885, the state of the art will be disclosed.

In my last application one form of the semi-elastic surface was shown as formed of a piece of string threaded through holes in one side wall of the channel in such manner as to project slightly into the path of or against the sides of the types and gently press or crowd them over toward and against the opposite side wall of the channel. I have found by ex-

periment that this form of semi-elastic anti-backlash is not only the simplest and cheapest, but is also the most effective form of anti-backlash in use. I also find that by allowing 55 the string to rest loosely within the channel, the outer end only being secured to prevent the longitudinal displacement of the string in the direction of the line of motion of the types, I increase the effectiveness of the device, since 60 the string or cord is then free to kink up or 65 pucker slightly under any retractile movement or pressure in the column of type, thereby increasing the resistance offered to the passage of the type in that direction without interfering with or increasing the normal resistance afforded to the advance of the types in the other and legitimate direction; but in order to insure this result and avoid any tendency of the types to work upward vertically, as 70 they are liable to do if the string does not extend parallel to the floor of the channel, it is desirable, when first starting to distribute into a channel, and until a column of type an inch or two long has been formed, to guide 75 and sustain the inner or free portion or end of the string or cord in the required alignment by means that, while they are positive in this respect, will not interfere with or prevent the puckering or kinking of the cord under back-pressure. I accomplish this by forming a groove parallel to the length of the channel in the side of the slug or type preceding and sustaining device, which groove is adapted to receive and sustain the adjoining portion of the 85 cord, confining the latter between itself and the side wall of the channel and lifting its free end up and feeding it to the succeeding types, as required by their advancement. By this means the perfect alignment of the full length 90 of the cord is attained before the slug passes beyond it, after which the types themselves, owing to their movement longitudinally through the channel, will successively preserve such proper relation of parts. 95

In my last application, No. 192,493, above referred to, the semi-elastic anti-backlash is used upon one side wall only of the type-containing channel.

For the purpose of more perfectly guiding 100 and sustaining the smaller sizes and thicknesses of types, I in the present case provide

each side wall of the type-channel with a section of semi-elastic material, the two being opposed to each other, so as to subject the types to an equal degree of friction or pressure upon each side. Where these sections are both formed of the loose string or cord, arranged and operating as hereinbefore mentioned, the opposite sides of the slug are formed with corresponding parallel grooves for the reception and guidance of either cord.

Another feature of my invention in connection with the slug consists in forming the latter with one or more grooves adapted to hold in position a loop or band of rubber, cord, or other elastic or semi-elastic material, for the purpose of increasing the frictional contact of the said slug with the side wall or walls of the type-containing channel. When the latter is formed with a high and a low wall, as is usual in the class of type-channels herein referred to, the cord or band is situated above the position of the upper edge of the lower side wall of the channel, and is arranged to project outward beyond the surface of the slug only upon one side of the latter, so that by reversing the slug in position within the channel, as required, its frictional contact with the upper side wall thereof may be increased or diminished. I am aware that a similar result is obtained in the slug shown and described in the patent to L. K. Johnson, No. 230,784, dated August 3, 1880; but in that case a flat metal spring riveted to the slug is employed. My object in this connection is to simplify and cheapen the construction of the device, and I do not seek to cover a friction-slug broadly.

An important feature of my present invention consists in forming the floor or bottom of the receiving end of the type-containing channel with a soft or semi-elastic receiving surface or cushion, against which the heels of the descending types will strike.

Heretofore the types have descended directly upon the metallic bottoms or spines of the channels, and since they fall vertically, or nearly so, and some of them from a height of between two and three inches, they have been liable to rebound to such an extent as to endanger their proper alignment or relative position within the channel. It is obviously of importance that the types should be handled as gently as possible, not only to avoid unnecessary wear, but also in order to prevent their turning upon their longitudinal axes, and by decreasing the jar or reaction at this point to the minimum degree I insure a more perfect and even line of type within the channel, and obviate the occurrence therein of turned or reversed types.

Incidental features of my invention consist in the means herein shown and described for providing for the suspension of the type-containing channel when required, and also in forming one end of the type-containing channel with elongated beads or interior projections of the side walls of the channel, for the purpose of retarding the passage of types at

that end, the said beads or ribs being corrugated or otherwise roughened transversely (or vertically) to augment frictional contact with the types. I do not, however, seek to cover herein, broadly, the use of these internal beads or ribs, as I elsewhere, in my application No. 201,104, claim one or more specially-arranged horizontal ribs at the receiving end of the channel, the special construction I seek to cover herein being the formation of the ribs with a roughened surface, consisting of lateral corrugations or their equivalent. I am also aware that in my application No. 201,105 the greater portion of the side wall of the channel is bent inward; but that is for the purpose of obtaining channels of maximum width externally, having continuous narrow internal type-passages.

In the accompanying drawings, in the first three figures of which portions of a reciprocating pusher and a vertical type-conduit are shown by way of illustration, Figure 1 is a side elevation of a type-containing channel embodying my improvements, the central portion being broken away; Fig. 2, a longitudinal section through the same, showing the slug or type-preceder in elevation; Fig. 3, a longitudinal section of the receiving end of the channel and adjoining portion of a vertical type-conduit forming part of a distributing apparatus; Fig. 4, a top view of the receiving end of the containing channel shown in Fig. 3; Fig. 5, a longitudinal section of the receiving end of the channel without the types or slug or type-preceder; Fig. 6, a transverse section of the channel and slug upon plane of line xx ; Fig. 7 is a side elevation of the grooved slug and type-preceder; Fig. 8, an end view of the same; Fig. 9, a top view of one extremity of the type-containing channel, a portion of each side wall being broken away to show the interior projections in section; and Fig. 10 is a longitudinal section of a slug, showing a form of groove which is less in depth at one extremity than at the other.

The type-containing channel A is formed from sheet metal struck up into the required form by suitable dies, as heretofore. It is preferably formed with a high wall, a , and a low wall, a' , for the purpose of exposing the heads of the types, &c., as set forth in previous application. The receiving end a^2 of the channel—that which engages with the vertical conduit and vibrating pusher in the distributing apparatus—is formed with walls a^3 , a^4 , of equal height. The height of these receiving end walls, a^3 , a^4 , is regulated with relation to the position of the vibrating pusher P when the channel is in the distributing apparatus.

It will be seen by reference to Figs. 1, 2, and 3, in which a portion of the reciprocating pusher P is shown by way of illustrating the relative positions of the parts referred to, that the upper edges of the end walls, a^3 , a^4 , pass underneath the pusher, and thereby allow the latter to forward the types the required dis-

tance with the channel, it being understood that the pusher P is a simple straight edge or plate without the usual comb-teeth or pusher-fingers.

5 The floor or bottom or the receiving end a' of the channel A is provided with a cushion or receiving surface, B, of a comparatively soft or semi-elastic material. There are a large variety of substances that may be used for this purpose, and their mode of application or attachment to the channel may be varied; but for the sake of illustration, and without designing to confine myself to the special construction shown in this respect, I have shown in the drawings a simple arrangement in which a band or section of tape or braid, b , of a width equal to about that of the interior of the channel, is passed through a hole, b' , in the floor or spine of the channel, and its ends tied together at the end thereof. Where this means is employed the free ends of the tape or braid b may be formed into a loop, b^2 , by which the channel may be suspended.

By reference to Fig. 3 it will be seen that 25 the cushion B is directly in the path of the heels of the types as they descend from the vertical conduit C.

Cords D D are attached to the side walls, a' , of the channel A, just back of its receiving 30 end a^2 , and at a height approximating that of the middle of the types when upright within the channel. These cords may be attached in any suitable or convenient manner. As shown in the drawings, one extremity of each cord is 35 simply knotted, while the other or free ends are passed through perforations d , formed in the side walls of the channel, and rest loosely therein.

The slug or type-preceder S is formed with 40 the grooves s upon either side, which coincide in position, when the slug S is opposite within the channel, with the holes or perforations d in the side walls of the channel, and consequently with the fixed ends of the cords 45 D D. The grooves s are parallel with the floor or bottom of the channel A.

Preparatory to distributing into the type-channel A, the cords are inserted in the grooves s in the slug, and the latter deposited in the 50 channel in position to receive and sustain the first types distributed. As the types increase in number and the line in length, the slug gradually raises the loose or free ends of the cords D D and insures their proper alignment 55 with relation to the channel and the types. The slug S is also formed, near its upper edge, with one or more grooves, s' , parallel to the grooves s , for the reception of a band of rubber or string, t , or other elastic or semi-elastic 60 material, which, by its contact with the side wall of the channel, will tend to retard the movement of the slug.

Where a channel having both a high and a low wall is used, as in the accompanying drawings, one of the grooves s' upon one side of the slug S is made sufficiently deep to receive the thickness of the cord t bodily, while the corre-

sponding groove upon the opposite side of the slug is either omitted or made very shallow, so as to cause the cord t upon that side to protrude more or less beyond the surface of the slug. By this means a reversible friction-slug is formed, since by turning the side upon which the cord t protrudes to the side of the channel upon which the short wall a' is situated the 75 cord t will be entirely free of either side wall, while by reversing the slug S the projecting portion of the cord t is brought into contact with the upper portion of the taller side wall, a , and by its compression between the 80 latter and the slug augments the resistance afforded against the movement of the slug in either direction.

The extremity of the containing-channel A, 85 opposite the receiving end, is formed with one or more beads, e , which project inward and are preferably roughened or corrugated, to afford a resisting-surface to the escape of the slug or types at that end of the channel. The same end of the channel is also formed with a 90 slot, f , in the floor or spine, for the purpose of affording a means of suspending the channel upon a hook or other support, when desired. The beads or corrugations e extend longitudinally within the channel.

95 The grooves s' may be formed in the ends of the slug S, instead of the sides, if preferred.

The grooves s may be inclined to the length of the slug S, as shown in Fig. 10—that is to say, one extremity of the groove s is made 100 shallower than the rest of the groove, for the purpose of pinching the cord more effectively at that point against the side wall of the containing-channel.

What I claim as my invention, and desire 105 to secure by Letters Patent, is—

1. A type-containing channel, substantially such as designated, provided with a type-receiving surface formed of a soft or semi-elastic material, substantially in the manner and for 110 the purpose described.

2. A type-containing channel, substantially such as described, both walls of which are provided with a semi-elastic type holding and sustaining material, substantially in the manner and for the purpose described.

3. In a type-containing channel, substantially such as designated, a type holding and retarding device consisting of a string or cord secured at one end to the side wall of the channel, while the other rests freely therein, for the purpose and substantially in the manner shown and described.

4. In combination with a type-containing channel, substantially as described, provided with one or more type-retaining cords arranged substantially as described, a type preceder or slug formed with one or more grooves for the reception and guidance of the said cord or cords, substantially in the manner and for the 125 purpose described.

5. In combination with a type-containing channel, substantially such as herein designated, a slug formed with one or more grooves

- for the reception of a band of rubber, cord, or other elastic or semi-elastic material, substantially in the manner and for the purpose described.
5. In combination with a type-containing channel, substantially such as herein designated, provided with side walls of different height, a reversible friction slug provided with a band or section of elastic or semi-elastic material which projects beyond its surface only upon one side, for the purpose and substantially in the manner described.
7. A type-containing channel, substantially such as herein designated, formed at one extremity with one or more inwardly-projecting beads or longitudinal ribs, which are corrugated or otherwise roughened transversely, for the purpose and substantially in the manner described.

A. AUGUSTUS LOW.
